ELBERTSON W. WAITE, OF NEW HAVEN, CONNECTICUT.

Letters Patent No. 80,845, dated August 11, 1868.

IMPROVEMENT IN CARRIAGE-PROP JOINTS.

The Schedule referred to in these Letters Patent and making part of the same.

TO ALL WHOM IT MAY CONCERN:

Be it known that I, ELBERTSON W. WAITE, of New Haven, in the State of Connecticut, have invented, made, and applied to use a certain new and useful Improvement in Joints for Carriage-Props; and I do hereby declare the following to be a full, clear, and exact description of the said invention, reference being had to the annexed drawing, making part of this specification, wherein—

Figure 1 is a section of said carriage-prop joint longitudinally, and

Figures 2 and 3 represent the same edgewise of the joint and bars.

Similar marks of reference denote the same parts.

Heretofore the joints for carriage-props have been forged upon the ends of the bars composing such props, the centre pins of such joints coming outside the line of one edge of the bars, in order that the bars may fold down closely together, and when unfolded, the ends of the bars will abut together and support the carriage-top.

Joints of the aforesaid character are costly to make, and difficult to finish up in a handsome manner, and these carriage-props, being in exposed positions, require to be made in such a manner as not to disfigure the carriage-top.

The nature of my said invention consists in a carriage-prop made with a double joint and link, so that the bars composing the prop can be finished externally nearly the same as they would be if there were no joint, the link entering the slot formed near each end of the bar, and being united by rivets or screws, one in each bar. Thereby a handsome, strong, durable prop is made, possessing all the folding-qualities of other carriage-props, but with a joint that is not prominent, as heretofore.

In the drawing, *a* and *b* represent portions of the ends of the metal bars composing the carriage-prop. These bars are to be of any desired length or pattern, and in the end of each a recess or slot is formed by a cutter, or forged of a size to receive one portion of the link *c*, that is formed with rounded ends, as shown, the screws, pins, or rivets *d* forming the centre of the arcs of circles described at the ends of said link, and also uniting the link with the bars, so that the parts will turn in folding or unfolding the bars.

The pins or rivets *d* are towards one edge of the bars *a* *b*, so that the ends come together at 2, to support the carriage-top, and at 3 the bars are rounded at one side of the ends, so as to allow the parts to fold together, in the form indicated by red lines.

This carriage-prop is neat and strong at the joint, and can be made for much less expense than those before employed.

What I claim, and desire to secure by Letters Patent, is—

The carriage-prop, made with the link *c* attached by the pins or screws *d* *d* to the bars *a* and *b*, in the manner and for the purposes specified.

In witness whereof I have hereunto set my signature, this seventh day of July, A. D. 1868.

Witnesses:

CHAS. H. SMITH,
GEO. T. PINCKNEY.
